US00D753718S

(12) **United States Design Patent**
Mariet et al.

(10) **Patent No.:** **US D753,718 S**
(45) **Date of Patent:** **** Apr. 12, 2016**

(54) **DISPLAY SCREEN OR A PORTION THEREOF WITH A GRAPHICAL USER INTERFACE**

(71) Applicant: **Google Inc.**, Mountain View, CA (US)

(72) Inventors: **Robertus Christianus Elisabeth Mariet**, Sunnyvale, CA (US); **Brian Douglas Cullinane**, Palo Alto, CA (US); **Manuel Christian Clement**, Felton, CA (US); **Andrew Timothy Szybalski**, San Francisco, CA (US); **Dmitri A. Dolgov**, Los Altos, CA (US)

(73) Assignee: **Google Inc.**, Mountain View, CA (US)

(**) Term: **15 Years**

(21) Appl. No.: **29/530,943**

(22) Filed: **Jun. 22, 2015**

Related U.S. Application Data

(62) Division of application No. 29/438,579, filed on Nov. 30, 2012, now Pat. No. Des. 735,214.

(51) **LOC (10) Cl.** **14-04**

(52) **U.S. Cl.** **USPC D14/492**

CLAIM

The ornamental design for a display screen or a portion thereof with a graphical user interface, as shown and described.

DESCRIPTION

The FIGURE is a front view of an image of a display screen or a portion thereof with a graphical user interface according to our design.

The broken line showing is included for the purpose of illustrating portions of the article and forms no part of the claimed design. The outermost dash-dot broken line illustrates a display screen or a portion thereof, and forms no part of the claimed design.
